REDUCTION CHOKE FOR OIL AND GAS
WELL SYSTEMS

Louis C. Clair, Bernice, La.

Application September 6, 1950, Serial No. 183,313

7 Claims. (Cl. 137—340)

1

My invention relates broadly to oil and gas well systems and more particularly to an improved method of operation and construction of non-freezing reduction choke for use in such systems.

One of the objects of my invention is to provide an improved construction of reduction choke for oil and gas well systems in which the thermodynamic characteristics of the oil and/or gas flow are employed to provide a temperature gradient in a reduction valve system insuring continuous flow of oil and/or gas without channeling and without freezing.

Another object of my invention is to provide a construction of reduction choke for oil and gas well systems in which a continuous flow of oil and/or gas may be maintained and the thermodynamic properties thereof utilized for maintaining flow, while prohibiting channeling and avoiding freezing in the flow path through the choke.

Still another object of my invention is to provide an improved construction of expansion chamber for oil and gas reduction chokes which is disposed axially within a cylindrical warming chamber which is elevated in temperature by the nascent temperature of the incoming oil and/or gas and the temperature cycle through the assembly balanced to insure against freezing while effecting the required reduction in pressure from 2000 lbs. or more to separation pressure.

Still another object of my invention is to provide a combined temperature controlled valve chamber and expansion valve by which the nascent oil and/or gas well pressure and temperature may be applied to the temperature controlled valve chamber and reduction in pressure effected through the expansion valve, while avoiding freezing during the drop from nascent oil and/or gas pressures to separation pressures.

Still another object of my invention is to provide a construction of reduction choke for oil and gas well systems in which an expansion chamber is concentrically disposed within a warming chamber and a reduction valve arranged within the expansion chamber and the said expansion chamber secured to a temperature gradient extending longitudinally thereof and a pressure flow in a controlled spiral direction from nascent gas and/or oil well temperature to a separation temperature and pressure while maintaining the system free of freezing.

Another object of my invention is to provide an improved construction of composition temperature control system and reduction choke for

oil and gas well systems in which a spirally arranged baffle surrounds an expansion chamber in which I provide a regulatable reduction valve associated with the spirally arranged baffle within in compact dimensions rendering the installation practicable in oil and gas well systems where pressures of the order of 2000 lbs. per square inch, or more, and temperatures of the order of 120° F. to 145° F. may be effectively controlled to develop temperatures of the order of 35° F.-40° F. at separator pressures of the order of 500-800 lbs. per square inch, the entire process being accomplished without freezing.

A further object of my invention is to provide a method of operation of oil and gas well systems whereby a spiralling movement of oil and/or gas is employed for controlling temperatures within an expansion chamber and pressure and temperature reductions effected without freezing.

Another and further object of my invention is to provide an improved method of operation of oil and gas well systems and an improved construction thereof as set forth more fully in the specification hereinafter following by reference to the accompanying drawings, in which:

Figure 1 illustrates the application of my improved method and apparatus to oil and gas well systems in connection with the separator system; Fig. 2 shows the application of my invention to the well head or Christmas tree of an oil or gas well; Fig. 3 is a theoretical diagram explaining the theory of operation of the improved method and apparatus of my invention; Fig. 4 is a transverse sectional diagram taken on line 4—4 of Fig. 1; Fig. 5 is a transverse sectional diagram on line 5—5 of Fig. 1; Fig. 6 is a side elevational view of the apparatus of my invention; Fig. 7 is a longitudinal sectional view on an enlarged scale through the apparatus of my invention; Fig. 8 is a view on an enlarged scale of the housing structure for the reduction valve and the reduction valve juxtaposed thereto as provided in the apparatus of my invention; and Fig. 9 shows the manner of assembling the parts of the apparatus of my invention.

My invention is directed to an improved method and apparatus for use in oil and gas well systems by which reductions in temperature encountered in oil and/or gas wells may be reduced and controlled without channeling and without freezing. I have determined after considerable research and development that the nascent temperatures and pressures of oil and/or gas may be employed in the production of forces around an expansion chamber for reducing a thermo-dynamic change

through the expansion chamber which may be so proportioned and regulated as will effect delivery of oil and/or gas at required reductions in temperature and pressure, but without channeling and without freezing. I have applied my invention to gas and/or oil wells having bottom hole pressures of 2000 lbs. per square inch, or more, at temperature ranges of from 120° F.-145° F. where the oil and/or gas is distributed through a spirally arranged warming chamber which is concentrically regulated to an expansion chamber and a reduction in temperature and/or pressure effected along a gradient which at the outlet of the expansion chamber may reach a pressure of 500-800 lbs. over a temperature range of from 35° F.-40° F., this control being accomplished without channeling and without freezing. Heretofore in the art reduction of pressure and temperature in oil and gas well systems has been accomplished by an accumulation of frost and ice which eventually automatically shuts down the oil and/or gas well. Heretofore it has been necessary to thaw out such frozen flow lines by specially constructed line heaters with a loss by evaporation of the lighter end products. The value of butane, methane, propane and ethane, and other end products, has considerably increased with industrial developments and it is important that these products be preserved which is accomplished by my method and system. The preservation of these end products is one of the major accomplishments of the method and equipment of my invention. Municipal and government regulations which make mandatory the prevention of waste in the recovery and preservation of all oil and gas well products are complied with by use of the improved method and system of my invention.

Referring to the drawings in more detail, reference character 1 schematically represents a separator connected through fluid discharge line 2 and control valve 3 to the inlet 4 of the cylindrical warming chamber 5 of the equipment of my invention. The cylindrical warming chamber 5 is connected with a coupling 6 at one end and with a header 7 at the other end. Because of the pressures involved these connections are made with strong welds. The material of the cylindrical warming chamber 5 is seamless steel pipe of very substantial strength. The coupling 6 projects beyond the end of a cylindrical warming chamber 5 and thereto is attached by a weld connection the choke cylinder 8. The choke cylinder 8 is also formed from Schedule 80, seamless steel pipe having a header 9 adjustably screw-threaded into the interior of the choke cylinder 8.

A 180° tube turn 10 formed of Schedule 80, seamless steel pipe connects between the side of the warming cylinder 5 adjacent the coupling 6 to a position at one side of the choke cylinder 8 and immediately adjacent the coupling 6. The tube turn forms a path for the oil and/or gas which is moved at high velocity in a spiral path through the interior of cylindrical warming chamber 5 by reason of the construction of spiral baffle 11 which I provide therein. The spiral baffle 11 is formed on the exterior of the tubular expansion chamber 12 which extends axially through the cylindrical warming chamber 5 and is screw-threaded into header 7 at one end and welded thereto at 7a and is screw-threaded into coupling 6 at 6b at the opposite end and welded thereto. These welds are accomplished during fabrication and before the application of cylindrical warming chamber 5 over the coupling 6 and to the header 7. The assembly is accomplished by linearly slid-

ing warming chamber 5 over header 7 and coupling 6 with choke cylinder connected with warming chamber 5 through turn pipe 10 as shown in Fig. 9.

The tubular expansion chamber 12 is axially aligned with the discharge pipe 14 screw-threaded into the end of header 7 and which may lead to the separator or the storage tanks. The tubular expansion chamber 12 receives at its opposite end the longitudinally extending choke seat 15, formed as illustrated more particularly in Fig. 8. The choke seat 15 has the end thereof screw-threaded in coupling 6 by means of screw-threads 15a on the exterior thereof, engaging the screw-threads 6a interiorly of coupling 6. The choke seat 15 is cylindrical in contour and extends from the screw-threaded recess 6a in coupling 6 into the interior of tubular expansion chamber 12. The choke seat 15 is provided at its inlet with a 12° frusto-conical valve seat or taper represented at 15b. The outlet for the choke seat 15 is provided with an expanding or outwardly flared nozzle 15c discharged into tubular expansion chamber 12.

A conically shaped valve 16 is aligned with the seat 15b and is variably controlled by means of rod 17 which extends through header 9.

In the form of my invention shown in Fig. 1, rod 17 is automatically operated by a diaphragm motor valve shown generally at 18. The diaphragm motor valve comprises a casing 19 which is suitably supported with respect to the header 9 for aligning the diaphragm motor valve 18 with the longitudinal axis of the warming cylinder 5 and the choke cylinder 8. The rod 17, carrying valve 16 thereon connects with an actuating rod 20, the axial position of which is controlled by the diaphragm 21. The diaphragm 21 is contained within a housing 22, one side of which is shown at 23 containing a gas inlet connection 24 and a gas discharge connection 25. The supply of gas through inlet connection 24 is controlled by the fluid level in the separator. As the fluid level in the separator rises to a given point a valve (not shown) is automatically opened admitting gas to inlet connection 24 thus raising the diaphragm 21 and moving rod 20 and connecting rod 17 to move valve 16 away from seat 15b, allowing fluid to discharge from the separator. After the fluid level is lowered in the separator the gas, that increased the pressure against diaphragm 21, is discharged automatically through discharge connection 25 closing the valve 16 against seat 15b and stopping the flow of gas and/or oil in choke cylinder 4 to tubular expansion chamber 12. Diaphragm 21 is biased to a position in which valve 16 is normally seated against valve seat 15b by means of coil spring 26 located within housing 22 and adjusted from the exterior thereof by a screw device 27. Thus, an automatic control of valve 16 may be effected.

However, there are numerous instances in which the control of valve 16 is required to be manually adjustable, as I have represented in Figs. 2 and 7. In this arrangement, valve rod 17 is externally screw-threaded as represented at 17a and is engaged in internal screw-threads 9a in header 9. The screw-threaded rod 17 extends exteriorly of the choke cylinder 8 and is provided with a manually engageable handle 28 thereon which may be tripped manually for moving valve 16 to any desired position, with respect to seat 15b. A stuffing box 29 is provided around rod 17 for controlling the gasket seal 30 and preventing leakage from choke cylinder 8.

The gas and/or oil at 2000 lbs., or more, bottom hole pressure, enters inlet connection 4 at one

side of the end of cylindrical warming chamber 5 and is directed in a spiral path around tubular expansion chamber 12 by the spiral baffle 11. The mass of spirally moving gas and/or oil traveling at high velocity is released at the opposite side of cylindrical warming chamber 5, at the opposite end thereof, into turn tube 10 and directed into one side of the end of choke cylinder 8. From choke cylinder 8 the high velocity high pressure flowing gas and/or oil is admitted in a selected quantity by choke valve 16 through valve seat 15b and through a choke seat 15 for release through expanding nozzle 15c into tubular expansion chamber 12 from which the flow is directed into discharge pipe 14.

While the apparatus and method of my invention is applicable to a wide variety of conditions existing in the petroleum industry, involving various temperatures and pressures, I have selected for purposes of illustration certain characteristics to which I have found my invention applicable. That is, for bottom hole pressures of 2000 lbs. per square inch, or more, at a temperature range of 120° F.-145° F. a spiral flow is secured confined by spiral baffle 11 within cylindrical warming chamber 5 and directed through the turn tube 10 into choke cylinder 8. The temperature gradient through the cylindrical warming chamber 5 reduces longitudinally of the cylindrical warming chamber 5 because of the cooling effect of the expansion chamber 12, particularly at the nozzle position 15c. In certain installations this temperature gradient has been such that the turn tube 10 for the initial temperatures of 120° F.-145° F., and the pressure heretofore noted, has been of the order of 80° F.-105° F. The gas and/or oil, of the characteristics noted, when passed through the reduction valve 16 and valve seat 15b and through choke seat 15 and expansion nozzle 15c reach a temperature range of the order of 35° F.-40° F. The oil and/or gas is discharged at discharge pipe 14 at this temperature range and at pressures of the order of 500-800 lbs. per square inch, and without freezing. The spiral control of the gas and/or oil prevents channeling and the concentric relationship of cylindrical warming chamber 5 and tubular expansion chamber 12 insures operation of the system above freezing temperature. Thus I am able to obtain within compact dimensions highly efficient operation of the method and system of my invention.

In Figs. 2 and 6, I have shown the application of my invention as herein described to the Christmas tree 31 of an oil or gas well leading through connection 32 to the valve 3 and inlet connection 4, as heretofore explained.

It will be observed that the piping leading to the cylindrical warming chamber 5 and the turn pipe 10 and the discharge pipe 14 are all of an interior diameter substantially equivalent to the radial distance between the cylindrical expansion chamber 12 and the inside wall of the warming cylinder 5 to eliminate all constrictions in the flow path except the constriction provided by the expansion valve 16 and coating with the seat 15b. That is to say the internal diameter of turn pipe 10 is always greater than the radial distance between the outside wall of cylindrical expansion chamber 12 and the inside surface of warming cylinder 5 and also the diameter of the pipe constituting inlet connection 4. The reduction therefore is effected in a zone which is at elevated temperature and freezing during the expansion process is thus prevented.

In Fig. 9 I have shown the manner of assem-

bling the apparatus of my invention in which the unit formed by the coupling 6 and header 7, united by the tubular expansion chamber 12, constitutes the base structure over which the cylindrical warming chamber 5 connected through turn tube 10 with choke cylinder 8 slides to assembled or disassembled position. The arrow indicates the direction of movement of the unit formed by cylindrical warming chamber 5, turn tube 10 and choke cylinder 8 during the disassembling of the apparatus. A reverse translatory movement is employed in assembling the apparatus. Thus the assembly and disassembly of the apparatus is very simple and may be effected without any requirement for any considerable degree of skill. That is the assembly merely requires the sliding of the cylindrical warming chamber 5 and the choke cylinder 8 into position over coupling 6 where the unit may be revolved to connect the end of warming cylinder 5 with the threaded header 7.

Sealed relationship is maintained between warming cylinder 5 and header 7 by a very tight screw-threaded connection supplemented by appropriate gaskets. A similar sealing connection is provided between the other end of warming cylinder 5 and coupling member 6 and between the end of choke cylinder 8 and coupling member 6 through appropriate gaskets. The header 9 connects with choke cylinder 8 through a tight screw-threaded connection supplemented by appropriate sealing gaskets.

The temperature of high pressure oil and gas wells with which the equipment of my invention is associated is related to the rate of production flow taken from the well. The greater the flow at the high well pressures, the higher will be the temperature. The internal freezing temperatures of high pressure oil and gas are much different than the freezing temperatures at atmospheric pressure. These factors have all been taken into account in the development of the equipment of my invention. The performance of the equipment of my invention has been very effective in preventing the freezing of hydrates that form in oil and gas lines at the point of pressure reduction. The fact that the incoming hot oil and gas is forced to flow in a path adjacent the choke cylinder 8 and around the expansion chamber 12 prevents freezing at the pressure reduction position. The gradual cooling of the incoming oil and gas which is caused by passing over the expansion chamber insures a very close temperature range for the expanded oil and gas that has passed through reduction chamber, and without the wide range temperature drop, therefore allowing hydrates that form in lines at the reduction point to pass without freezing.

While I have described my invention in certain of its preferred embodiments I realize that modifications may be made, and I desire that it be understood that no limitations upon my invention are intended other than may be imposed by the scope of the appended claims.

What I claim as new and desire to secure by Letters Patent is as follows:

1. A reduction choke for oil and gas well systems comprising a tubular expansion chamber, a cylindrical screw-threaded header on one end thereof, a coupling member on the other end thereof and extending radially therefrom, a spiral baffle formed on the exterior of said chamber between said header and said coupling member, a cylindrical warming chamber, a choke chamber, a tubular member interconnecting said chambers,

said cylindrical warming chamber being screw-threaded to engage said screw-threaded header, both said warming chamber and said choke chamber being interconnected by said coupling member, a cylindrical header carried by the end of said choke chamber and an adjustable valve member carried by said last mentioned header and adjustable therein for controlling said tubular expansion chamber.

2. A reduction choke for oil and gas well systems comprising a tubular expansion chamber, a cylindrical header on one end thereof, a coupling member on the other end thereof and projecting radially therefrom; a spiral baffle formed on said chamber between said header and said coupling member and extending radially for a distance corresponding to the radii of said cylindrical header and said coupling member, a cylindrical warming chamber, a choke chamber connected with the end of said cylindrical warming chamber, the diameters of said chambers being such that they establish a snug fit when moved in an axial direction over said coupling chamber and said header, and means securing said cylindrical warming chamber to said header and to said coupling member.

3. A reduction choke for oil and gas well systems as set forth in claim 2 in which an expansion valve is carried by said coupling member and connected with said tubular expansion chamber.

4. A reduction choke for oil and gas well systems as set forth in claim 2 in which an expansion valve is carried by said coupling means and projects through said coupling member and concentrically into said tubular expansion chamber and wherein an adjustable valve is carried by said choke chamber and variably adjustable for adjusting said expansion valve.

5. A reduction choke for oil and gas well systems as set forth in claim 2 in which the discharge connection is established through said head with said tubular expansion chamber and in which an intake connection is provided in one side of said warming chamber and in which a discharge connection extends from said warming chamber in a position adjacent said coupling member and opposite said intake connection.

6. A reduction choke for oil and gas well sys-

tems as set forth in claim 2 in which the discharge connection is established through said head with said tubular expansion chamber and in which an intake connection is provided in one side of said warming chamber, a discharge connection extending from said warming chamber in a position adjacent said coupling member and opposite said intake connection, an expansion valve carried by said coupling member and adjustable to various positions in said choke chamber, and a connection from said last mentioned discharge connection to said choke chamber on the opposite side of said coupling chamber and in a position immediately adjacent said expansion valve.

7. A reduction choke for oil and gas well systems including a cylindrical warming chamber having an intake in one side adjacent the end thereof, an outlet located at the opposite side adjacent the other end thereof, a choke chamber coaxially aligned with one end of said warming chamber, a coupling member extending between said warming chamber and said choke chamber coincident with the axis of each of said chambers, a connection between said choke chamber and the said outlet of said warming chamber, an expansion valve having a tubular expansion chamber supported by said coupling member and projecting through said warming chamber, an adjustable valve supported by said choke chamber and adjustable axially of said tubular expansion chamber from the exterior of said choke chamber, and a discharge connection for the tubular expansion chamber located at the end of said warming chamber adjacent the intake end thereof.
